Term of patent 14 years

(Cl. D35—2)

FIG. 1

FIG. 2

FIG. 3

FIG. 1 is a perspective rear view of a rotary tiller showing my new design;

FIG. 2 is a perspective view of the left side thereof;

FIG. 3 is a perspective view looking in the direction of the right rear corner thereof;

FIG. 4 is a top plan view thereof; and

FIG. 5 is a front elevation thereof and it is understood that the tines, partially shown, are continuous across the shaft element as indicated by the dashed lines.

The dominant features of my design reside in the full line portions of the drawings.

I claim:

The ornamental design for a rotary tiller, as shown and described.
